BOTTLE OPENER

Willie T. Pearson, Jackson, Miss.

Application January 27, 1939, Serial No. 253,181

6 Claims. (Cl. 65—46)

This invention relates to bottle openers of the character for removing crown caps from bottles, and has for the primary object the provision of a device of this character which besides providing a cap remover possessing a maximum amount of efficiency also may be employed for carrying or otherwise handling a bottle before the removal of the cap therefrom and obviates the necessity of placing the hands in direct contact with a wet, cold bottle, besides permitting the bottle to be handled in a highly sanitary manner and further will grip and retain the cap after its removal from the bottle so that the cap may be manually released with ease whenever it is convenient to deposit the cap in a collection receptacle or like device.

With these and other objects in view, the invention consists in certain novel features of construction, combination and arrangement of parts to be hereinafter more fully described and claimed.

For a complete understanding of my invention, reference is to be had to the following description and accompanying drawing, in which

Figure 1 is a side elevation illustrating a bottle opener constructed in accordance with my invention and showing the application thereof to a cap on a bottle.

Figure 2 is a fragmentary side elevation showing the device gripping the cap after the latter's removal from the bottle.

Figure 3 is a top plan view illustrating the device.

Figure 4 is a detail sectional view taken on the line 4—4 of Figure 2.

Referring in detail to the drawing, the numeral 5 indicates an elongated handle, one end of which is rounded to present curved faces 6 lying at opposite sides of the extremely pointed portion 7 of the handle. The handle 5 gradually tapers toward the non-rounded end thereof.

A wear plate 7' of elongated formation is secured on one edge of the handle 5 by being provided with tines 8 driven into the handle. The wear plate 7' during the use of the device as a bottle opener contacts the cap and receives all of the strain or wear during the fulcruming of the handle on the cap and which will be hereinafter more fully described in detail.

The handle 5 is equipped with spaced pins 10 and 11 adjacent to the pointed end thereof and a cap gripping device 12 is journaled on one of the pins, or as clearly shown in the drawing, on the pin 10 while the pin 11 acts as a stop for the pivotal movement of the gripping element 12

in one direction on the handle. The pins 10 and 11 are tied together by elongated washers 13.

The gripping element 12 comprises a pair of substantially U-shaped jaws 14 and 15 connected integrally with each other by coiled portions 16 through which the pin 10 extends for the pivoting of the gripping element on the handle, also the coiled portions act as tension mediums tending to urge the jaws in the direction of each other 10 or into position for gripping a cap 16' on a bottle 17. The jaws 14 and 15 normally assume a position with respect to each other in which said jaws are spaced from one another. However, the distance between the jaws is less than the external 15 diameter of the cap 16'.

The jaw 14 or the connecting portion 17' thereof has a compound curvature thereto defining projections to engage under the flange of the cap 16' when adapted thereto. Also said connecting portion has a slight arcuate curvature from end to end thereof. The connecting portion 18 of the jaw 15 has an arcuate curvature so that it will readily conform to the contour of the neck of the bottle.

In use, the handle 5 is placed above the cap of a bottle with the jaws 14 and 15 engaging said cap and by a downward pressure on the handle the jaws will be caused to spread and slide downwardly over the cap and engage under the flange 30 of the cap at opposite sides of the neck of the bottle, as clearly shown in Figure 1, with the wear plate 7 coming to rest on the top of the cap. The device thus applied to the cap and bottle provides a very efficient handle for the lifting, carrying 35 or otherwise handling of the bottle. When it is desired to remove the cap from the bottle a downward pressure is placed on one end of the handle with the latter fulcruming on the cap and with the latter gripped by the jaws, said cap will be effectively and easily removed from the bottle, remaining gripped between the jaws, as shown in Figure 2, so that through a slight manual effort the jaws may be separated to free the cap for gravitation into a collecting receptacle or 40 similar device, obviating the cap from falling immediately on its removal from the bottle.

Thus it will be seen that a very efficient bottle opener has been provided wherein a cap can be easily and conveniently removed without damage 50 to the bottle or danger of injuring the person using the device and further it will be seen that prior to the removal of the cap and on the application of the opener to the cap, said opener may be employed for carrying the bottle from 55

one place to another and for wrapping the bottle without placing the hands in direct contact therewith.

Further, it will be seen that a device of this kind may be manufactured and sold at a low cost and also it is to be understood that while the gripping element 12 has been described and shown as being adapted to a specially constructed handle, it is to be understood that through a very slight rearrangement of the gripping element its application may be easily made to a conventional type of cap remover commonly employed on the market and having a handle with a ring-like head provided with spaced projections to engage under the flange of the cap while the ring-like head engages on the top of the cap.

It is believed that the simplicity and advantages of this invention will be perfectly apparent to those skilled in the art to which such a device relates and while I have herein set forth a satisfactory embodiment of the invention, it is to be understood that such changes therefrom as fairly within the scope of my claims may be resorted to when desired.

Having described the invention, I claim:

1. In a device of the character described, an elongated handle to engage with a cap of a bottle, a wear plate secured on the handle to contact the cap, a gripping element pivotally mounted on the handle adjacent one end thereof and including spaced resilient jaws to receive therebetween and grip a cap on the application of the wear plate onto the top face of the cap to permit carrying of the bottle by the handle and to coact with the handle in removing the cap from the bottle and retaining the cap on the handle until manually released from the gripping element.

2. In a device of the character set forth, an elongated handle to engage the cap of a bottle, a pivot pin carried by the handle adjacent one end thereof, a gripping element journaled on said pivot pin and including a pair of integrally connected substantially U-shaped jaws provided with coiled tensioned portions receiving the pivot pin and acting to urge the jaws in the direction of each other for a limited distance to permit said jaws to spread and pass over a cap of a bottle and grip the cap under the lower edge thereof at opposite sides of the bottle.

3. In a device of the character set forth, an elongated handle to engage the cap of a bottle, a pivot pin carried by the handle adjacent one end thereof, a gripping element journaled on said pivot pin and including a pair of integrally connected substantially U-shaped jaws provided with coiled tensioned portions receiving the pivot pin and acting to urge the jaws in the direction of each other for a limited distance to permit said jaws to spread and pass over a cap of a bottle and grip the cap under the lower edge thereof at opposite sides of the bottle, one of said jaws including a connecting portion having a compound curvature to provide projections to engage under the cap and the other jaw including a connecting portion arcuately curved to conform to the contour of a bottle.

4. In a device of the character set forth, an

elongated handle to engage the cap of a bottle, a pivot pin carried by the handle adjacent one end thereof, a gripping element journaled on said pivot pin and including a pair of integrally connected substantially U-shaped jaws provided with coiled tensioned portions receiving the pivot pin and acting to urge the jaws in the direction of each other for a limited distance to permit said jaws to spread and pass over a cap of a bottle and grip the cap under the lower edge thereof at opposite sides of the bottle, one of said jaws including a connecting portion having a compound curvature to provide projections to engage under the cap and the other jaw including a connecting portion arcuately curved to conform to the contour of a bottle, and a stop pin carried by the handle adjacent the pivot pin for limiting the pivotal movement of the gripping element in one direction.

5. In a device of the character set forth, an elongated handle to engage the cap of a bottle, a pivot pin carried by the handle adjacent one end thereof, a gripping element journaled on said pivot pin and including a pair of integrally connected substantially U-shaped jaws provided with coiled tensioned portions receiving the pivot pin and acting to urge the jaws in the direction of each other for a limited distance to permit said jaws to spread and pass over a cap of a bottle and grip the cap under the lower edge thereof at opposite sides of the bottle, one of said jaws including a connecting portion having a compound curvature to provide projections to engage under the cap and the other jaw including a connecting portion arcuately curved to conform to the contour of a bottle, a stop pin carried by the handle adjacent the pivot pin for limiting the pivotal movement of the gripping element in one direction on the handle, and tie plates connecting the stop pin with the pivot pin.

6. In a device of the character set forth, an elongated handle to engage the cap of a bottle, a pivot pin carried by the handle adjacent one end thereof, a gripping element journaled on said pivot pin and including a pair of integrally connected substantially U-shaped jaws provided with coiled tensioned portions receiving the pivot pin and acting to urge the jaws in the direction of each other for a limited distance to permit said jaws to spread and pass over a cap of a bottle and grip the cap under the lower edge thereof at opposite sides of the bottle, one of said jaws including a connecting portion having a compound curvature to provide projections to engage under the cap and the other jaw including a connecting portion arcuately curved to conform to the contour of a bottle, a stop pin carried by the handle adjacent the pivot pin for limiting the pivotal movement of the gripping element in one direction on the handle, and tie plates connecting the stop pin with the pivot pin, said end of the handle located adjacent to the pivot pin being rounded to form a pointed portion with curved faces arranged at opposite sides thereof.

WILLIE T. PEARSON.
